US0D1106162S

(12) **United States Design Patent** (10) **Patent No.:** **US D1,106,162 S**
(45) **Date of Patent:** **** Dec. 16, 2025**

(54) **COVER FOR ELECTRONIC DEVICE**

(71) Applicant: **SPIGEN KOREA CO., LTD.**, Seoul (KR)

(72) Inventor: **Jong Eun Kim**, Seoul (KR)

(73) Assignee: **SPIGEN KOREA CO., LTD.**, Seoul (KR)

(**) Term: **15 Years**

(21) Appl. No.: **29/884,459**

(22) Filed: **Feb. 12, 2023**

(51) LOC (15) Cl. **14-01**

(52) U.S. Cl.

USPC **D14/205**

(58) **Field of Classification Search**

(57) **CLAIM**

The ornamental design for a cover for electronic device as shown and described.

DESCRIPTION

FIG. 1 is a front perspective view of a cover for electronic device showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines throughout the drawing figures depict portions of the cover for electronic device that form no part of the claimed design.

1 Claim, 7 Drawing Sheets
